UNITED STATES PATENT OFFICE.

PETER H. MURPHY, OF PITTSBURG, PENNSYLVANIA.

OUTSIDE METAL CAR-ROOF.

968,183.

Specification of Letters Patent. Patented Aug. 23, 1910.

Application filed April 14, 1909. Serial No. 489,836.

To all whom it may concern:

Be it known that I, PETER H. MURPHY, a citizen of the United States, and a resident of the city of Pittsburgh, county of Allegheny, and State of Pennsylvania, have invented certain new and useful Improvements in Outside Metal Car-Roofs, of which the following is a specification.

My invention relates to car roofs and has 10 for its objects to improve the protection of the ridge seam; to relieve the corner caps of the weight of the running board; to provide for the fastening of the running board; and to secure other advantages hereinafter appearing.

The invention consists principally in 15 grooved caps straddling the ridge seam throughout the full width of the sheets and adapted to be held by the corner caps.

It also consists in modifying the ends of 20 the endmost seam caps to provide for the fastening thereof.

It also consists in adapting the corner caps to secure the running board saddles; and 25 it also consists in the parts and in the arrangements and combination of parts hereinafter described and claimed.

In the accompanying drawing, wherein 30 like symbols refer to like parts wherever they occur,—Figure 1 is a vertical longitudinal sectional view of the end portion of a car embodying my invention; Fig. 2 is a side view of a corner cap showing in section a running board saddle engaged thereby; 35 Fig. 3 is a detail view of the bolt for securing the corner cap, the head of said bolt being shown in section; Fig. 4 is an elevation of a corner cap with the running board saddle interlocked therewith; Fig. 5 is a 40 plan view of a corner cap with a running board saddle interlocked therewith; Fig. 6 is a side elevation of the endmost ridge cap with a running board saddle shown in section; Fig. 7 is an end elevation of the endmost ridge cap; Fig. 8 is a side elevation of 45 a ridge cap for the intermediate sheets; and Fig. 9 is an end elevation of the ridge cap.

In the present invention, the metal roof sheets 1 rest upon a wooden sheathing 2 50 which is supported by a sub-structure of common type. The metal roof sheets are arranged transversely of the car and are connected at the sides by raised seams or ribs 3 of any suitable type. The sheets extend upwardly from the eaves to the ridge where they are likewise connected by raised seams

or ribs of any suitable type. As illustrated in the drawing, these ridge seams are formed by the overlapping of rebent upwardly projecting flanges on the ridge ends of the 60 sheets. The sheets are movably held in place at the eaves by clips or other suitable devices; and they are movably held in position at the ridge by corner caps 5 having four-way grooves or channels therein adapted to 65 accommodate the ridge and transverse seams. In consequence of this well known method of fastening the metal sheets, they are free to move to a limited extent relatively to the 70 wooden sheathing.

In order to protect the ridge portions of the sheets, a seam cap 6 is provided therefor. This seam cap is a strip of sheet metal having a longitudinal groove therein of suitable dimensions to accommodate the ridge seam 75 or upwardly extending flanges of the roof sheets. The ends of these seam caps reach close to the side flanges of the roof sheets so that said ends are covered by the corner caps. The marginal portions of said seam 80 cap lie flatwise against the roof sheets; and as the end portions thereof are of substantially the same width as the corner caps, the corner caps bear solely against them. By this arrangement, the seam caps constitute 85 wear plates and to a considerable extent relieve the roof sheets of the wear and other effects that would be produced if the corner caps bear directly on the roof sheets.

Each of the corner caps has a bolt hole 7 90 in its topmost portion at the point of intersection of its grooves or channels. Around the margin of this hole is formed a raised rib 8 of annular or polygonal contour. Extending downwardly through said bolt hole 95 is a threaded bolt 9 whose lower end extends through the ridge pole 10 of the car and is secured by a suitable nut 11. The head or upper end of the bolt is provided on its under surface with a groove or channel 12 100 adapted to receive the upstanding rib of the corner cap. By this arrangement, the bolt hole is protected from the weather.

Projecting horizontally from the upper portion of the corner cap in the direction of 105 the length of the car is an angular hook or securing member 13 preferably integral therewith. The outer end portion 14 of this securing member is turned downwardly; and located between the body of the corner cap and the downturned portion of the hook 110 is a ridge saddle 15. The lower portion of

this ridge saddle is beveled or inclined to conform to the pitch of the car roof, and the top of the running board saddle is immediately under the horizontal projecting portion 13 of the corner cap. In some cases, it is desirable to groove the upper surface of the running board saddle (as illustrated in Fig. 4) so that the top thereof may be flush with or slightly above the top of the corner cap. By this arrangement, the respective running board saddles are held in place by the corner cap and alongside thereof, without being materially weakened and without imposing their weight upon the corner caps. 15 In the case of each of the endmost seam caps 16, special provision is made for securing the ends thereof. The inner end of the endmost seam cap has longitudinal slits of sufficient length to reach beyond the corner cap; and the slit corner portions 17 of said seam cap are turned up alongside of the running board saddle and are secured thereto by nails or other suitable means. The outer end of each of the endmost seam caps 20 is bent downwardly, and the downturned portion 18 thereof is nailed or otherwise suitably secured to the end molding. The downturning of the end is effected in such manner that the seam is completely closed by the material of the seam cap, so that the weather is excluded from said ridge seam. Resting upon the running board saddles are suitable running boards 19 whose ends are supported by brackets 20 mounted on the 25 ends of the car.

Among the advantages of the present invention, it is noted that the ridge seams are fully protected throughout the width of the sheets and that the protective caps extend 30 beneath the corner caps and are secured thereby. It is also noted that, as there is no material mutilation of the running board saddles, they may be made of thinner stock than has heretofore been the practice. It 35 is also noted that, as the weight of the running boards is taken from the corner caps there is less risk of the roof sheets being pinched by the corner caps, and besides, the weight on the roof sheets is distributed over 40 a larger area. It is also noted that, on account of the simplicity of the several devices there is little risk of careless workmen making mistakes in the application thereof.

Obviously the construction hereinbefore 45 described admits of considerable modification without departing from my invention

and I do not wish to be restricted to the details above set forth.

What I claim is:

1. A car roof comprising roof sheets extending from eaves to ridge and movably connected at their sides and inner ends by raised seams, grooved seam caps covering the ridge seams, grooved corner caps at the ridge covering the end portions of said ridge caps and 60 the side seams, and running board saddles arranged transversely of the car and secured to said corner caps alongside thereof, the inner ends of the side portions of the endmost seam cap being turned up and secured 65 to the adjacent running board saddle.

2. A car roof comprising roof sheets extending from eaves to ridge and movably connected at their sides and inner ends by raised seams, grooved seam caps covering the 75 ridge seams, the endmost ridge cap being secured at its outer end to the end of the car, grooved corner caps at the ridge covering the adjacent end portions of the ridge caps and the inner ends of the side seams, and 80 running board saddles arranged loosely, transversely of the car alongside of the corner caps; each of said corner caps being secured to the top of the car by a bolt passing therethrough and each of said corner 85 caps also having a saddle portion adapted to overhang the adjacent running board saddle to hold the same in place, the inner ends of the side portions of the endmost ridge cap being secured to the adjacent running board 90 saddle.

3. A car roof comprising roof sheets extending from eaves to ridge and movably connected at their sides and ridge ends by raised seams, and grooved corner caps at the 95 ridge covering the end portions of said ridge and side seams, and wear plates intervening between said corner caps and said roof sheets, said wear plates being grooved to bridge the ridge seam and extending substantially the full width of a sheet and being of substantially the same width as the corner cap.

In witness whereof I have signed my name to this specification in the presence of two 105 subscribing witnesses this 12th day of April, 1909, at Pittsburg, Pennsylvania.

PETER H. MURPHY.
